(57) **CLAIM**

The ornamental design for a cryopreservation and storage device, as shown and described.

DESCRIPTION

FIG. 1 is a perspective view of the cryopreservation and storage device;

FIG. 2 is an exploded perspective view of the cryopreservation and storage device with the inner straw removed from the outer sleeve;

FIG. 3 is a front view of the inner straw;

FIG. 4 is a rear view of the inner straw;

FIG. 5 is a top view of the inner straw;

FIG. 6 is a bottom view of the inner straw;

FIG. 7 is a left side view of the inner straw;

FIG. 8 is a right side view of the inner straw;

FIG. 9 is a front (as well as rear, top and bottom) view of the outer sleeve;

FIG. 10 is a left side view of the outer sleeve; and,

FIG. 11 is a right side view of the outer sleeve.

The dot/dash broken line seen in FIG. 2 is included for the purpose of illustrating the order of assembly of the exploded view of the cryopreservation and storage device and forms no part of the claimed design.
